UNITED STATES PATENT OFFICE.

VINCENT A. TAYLOR, OF BEDFORD, AND JAMES D. CLOUGH, JR., OF CLEVELAND, OHIO.

TRAVERSE SANDING-MACHINE.

SPECIFICATION forming part of Letters Patent No. 532,348, dated January 8, 1895.

Application filed April 24, 1894. Serial No. 508,803. (No model.)

To all whom it may concern:

Be it known that we, VINCENT A. TAYLOR, of Bedford, and JAMES D. CLOUGH, Jr., of Cleveland, in the county of Cuyahoga, State 5 of Ohio, have invented certain new and useful Improvements in Traverse Sanding-Machines; and we do hereby declare the following to be a full, clear, and exact description of the invention, such as will enable others 10 skilled in the art to which it pertains to make and use the same.

Our invention relates to improvements in vertical traverse sandpapering, smoothing or polishing-machines, the primary object being 15 to construct a machine wherein one or more vertically-arranged sand-papering or polishing-drums are employed, which drum or drums have bearing at either end, and wherein the upright frame that carries said bearings and 20 the drum or drums, is reciprocated vertically during the rotation of the drum or drums in the operation of the machine, by which construction the edges of irregular work can be accurately squared, smoothed or polished, the 25 sand-papering, smoothing or polishing-drum or drums not being liable to vibrate in the operation of the machine.

A preferable construction of machine embodying our invention is illustrated in the accompanying drawings, wherein—

Figure 1 is a front side elevation of the same, and Fig. 2 is a left hand side elevation relative to Fig. 1. Portions are broken away and in section in said figures to more clearly 35 show the construction. Fig. 3 is an enlarged top view in section on line 3—3, Fig. 1.

Referring to the drawings, A A designate two upright standards, frames or housings that are located a suitable interval apart and 40 connected at the top and bottom by cross-beams or girders C and D. The sandpapering, smoothing or polishing drum or drums are located at the front side of the machine. The machine illustrated has two of said drums 45 marked E E that are arranged vertically and located a suitable distance apart. Each drum is operatively mounted upon a shaft G that, at or near each end of the respective drum, has bearing in a box g rigid with a frame H 50 that is adapted to slide up and down between the pair of housings or upright frames A A,

said reciprocating-frame engaging suitable slide-ways *a* formed in the supporting-frames or housings. The arrangement of parts is such that the forward side of the sand-papering, smoothing or polishing drum or drums is somewhat forward of the upright supporting-frames or housings, and a table I, suitably supported from said frames or housings, is provided at the forward side of the machine for 60 receiving the work whose edges are to be squared, smoothed or polished, said table being cut away or slotted vertically, as at I', to accommodate the location and operation of the sand-papering or polishing-drum or 65 drums.

Suitable means are employed for effecting the reciprocation of the drum-carrying frame H during the rotation of the drum or drums. Preferable means for the purpose consists of 70 a vertically-arranged double-feed-screw K that is shown located centrally between the two sand-papering, smoothing or polishing drums, and, at its upper end, terminates in a plain or unthreaded portion K' that extends 75 upwardly through the top cross-beam C, and has two collars k fixed thereon above and below said beam, respectively, to prevent end-wise movement of the screw. The feed-screw also has bearing in a box K² rigid with reciprocating-frame H, said connection of the feed-screw with said frame also assisting in guiding and steadyng the frame in the operation of the latter. Feed-screw K being of the double-feed variety,—the same having a 80 right handed and a left handed spiral groove,—is adapted to feed frame H in opposite directions alternately, frame H carrying a swiveled dog L adapted to engage the grooves of the screw. Said grooves are in 85 open relation with each other at their ends and the arrangement of parts is such that dog L will ride up the one groove in the screw, and down the other groove, said dog carrying frame H with it. Feed-screw K, preferably 90 at its lower end, is intergeared, as at M, with an upright shaft O that is located a suitable distance rearwardly of and arranged parallel with the feed-screw. Shaft O is suitably supported from frames or housings A, and, at its 95 upper end, is provided with a driving-pulley O'. Shaft O is provided with a drum, O², the 100

length whereof is equal to the traverse of the sand-papering, smoothing or polishing drums and the pulleys on said drums. Drum O² is shown operatively connected, by means of a single belt, P, with pulleys R R, operatively mounted, respectively, upon the different smoothing or polishing drum - supporting-shafts, said pulleys R R being provided, respectively, with an external flange R' at either end to prevent automatic displacement of the belt from the pulleys. The belt, of course, must travel with the sand-papering, smoothing or polishing-drums in the reciprocation of said drums. Frame H and the sanding-drums are counterbalanced to facilitate the reciprocation of the same. A preferable manner of counterbalancing said drums is by means of weights, S. Two weights S are employed in the machine illustrated and are attached to the one end of a cable, rope or chain, T, that leads thence upwardly to and over a pulley U suitably supported by the adjacent supporting-frame or housing A, and thence leads to reciprocating-frame H to which it is suitably attached, as at T'.

The pieces of wood or work whose edges require squaring, smoothing or polishing are placed upon table I and fed in a horizontal plane back and forth across the revolving sanding or polishing surface of the sanding-drum or drums.

Our improved machine is not only exceedingly simple in construction and durable, but the facing or polishing surfaces cannot possibly vibrate during their operation, and hence the edges of the work can, with great facility, be accurately squared, smoothed or polished.

What we claim is—

1. In a machine of the variety indicated, the combination of two upright supporting-frames or standards, a reciprocating frame located between and adapted to slide up and down said frames or standards, said reciprocating-frame bearing one or more vertically arranged sand-papering, polishing or smoothing drums, means for actuating said frame, and means for rotating the drum or drums

during the reciprocation of the aforesaid frame, the arrangement of parts being substantially as shown, for the purpose specified. 50

2. In a machine of the variety indicated, the combination of two upright supporting-frames or standards, a reciprocating-frame located between and adapted to slide up and down said frames or standards, said reciprocating-frame bearing one or more vertically-arranged sand-papering, smoothing or polishing-drums, and provided with a swiveled dog L, of a vertically-arranged double feed-screw K engaged by said dog, suitable means for rotating said screw, and suitable means for rotating the aforesaid drum or drums, substantially as set forth. 60

3. In a machine of the variety indicated, the combination of two upright supporting-frames, housings or standards located a suitable interval apart, a vertically - arranged reciprocating - frame located between and adapted to slide up and down said housings or standards, two vertically-arranged sand-papering, smoothing or polishing-drums borne by said reciprocating - frame and located a suitable interval apart, a vertically-arranged rotating drum or elongated pulley suitably supported rearward of the sand - papering, smoothing or polishing-drums, a pulley operatively connected with each of said smoothing or polishing-drums and operatively connected with the aforesaid elongated pulley by a single belt, a table for receiving the work to be sand-papered, squared or smoothed, and suitable means for actuating the aforesaid reciprocating-frame, the arrangement of parts being substantially as shown, for the purpose specified. 70

In testimony whereof we sign this specification, in the presence of two witnesses, this 31st day of March, 1894.

VINCENT A. TAYLOR,
JAMES D. CLOUGH, JR.
